UNITED STATES PATENT OFFICE

131,686

DESIGN FOR A MILITARY VEHICLE HEADLAMP UNIT

William B. Johnson, United States Army

Application January 23, 1942, Serial No. 105,390

Term of patent 3½ years

To all whom it may concern:

Be it known that I, William B. Johnson, United States Army, a citizen of the United States, have invented a new, original, and ornamental Design for a Military Vehicle Headlamp Unit, of which the following is a specification, reference being had to the accompanying drawing, forming part thereof.

Fig. 1 is a side elevational view of a military vehicle headlamp unit showing my new design, and

Fig. 2 is a front elevational view thereof.

I claim:

The ornamental design for a military vehicle headlamp unit, as shown.

WILLIAM B. JOHNSON.
